UNITED STATES PATENT OFFICE.

HAROLD W. SHONNARD, OF UPPER MONTCLAIR, NEW JERSEY, ASSIGNOR TO CRUCIBLE STEEL COMPANY OF AMERICA, OF PITTSBURGH, PENNSYLVANIA, A CORPORATION OF NEW JERSEY.

AUTOMOBILE TORPEDO.

1,302,982.

Specification of Letters Patent.

Patented May 6, 1919.

Application filed March 31, 1917, Serial 158,902. Renewed January 27, 1919. Serial No. 273,483.

To all whom it may concern:

Be it known that I, HAROLD W. SHONNARD, residing at Upper Montclair, in the county of Essex and State of New Jersey, a citizen 5 of the United States, have invented or discovered certain new and useful Improvements in Automobile Torpedoes, of which improvements the following is a specification.

10 In the actual construction of automobile torpedoes, the usual practice is to provide a pair of oppositely rotatable tandem propellers and to provide, coaxially therewith, a passageway for the escape from the torpedo of the spent or exhaust motive fluid. The objection to such an arrangement is that in order to preserve the desired contour of the tail and at the same time to provide an 15 adequate central exhaust passageway, it becomes necessary to use large diameter propellers, so large in fact that the skin friction of the propellers is increased to such an extent that there is a substantial loss of motive power. To surmount this, as well as 20 other prejudicial features incident to the use of tandem propellers with central exhaust, twin propellers with an intermediate and propeller-separating exhaust passageways have been suggested. However, in such 25 prior suggestions, the constructions are such as to preclude the development of maximum power efficiency.

30 In view of the foregoing considerations, it is the object of my invention to provide 35 an automobile torpedo wherein the tail construction and arrangement of propelling mechanism and exhaust ports is such that the propellers may be constructed to develop a maximum torpedo speed at maximum propeller and motive power efficiency.

40 In the accompanying sheets of drawings, forming part of my specification, I have illustrated the preferred embodiment of my invention. Figure 1 is a combined plan and 45 longitudinal horizontal sectional view of a portion of a torpedo; Figs. 2 and 3 are, respectively, side and rear end views of the torpedo tail; and Fig. 4 a sectional view taken on the line IV—IV, Fig. 3.

50 In the practice of my invention I provide twin propellers having their axes of rotation lying in a common substantially horizontal plane and having their blades overlapping midway between such axes; and, 55 correlated with such propeller arrangement,

I provide an exhaust conduit independently of the propeller shafts. Preferably I place the tail vanes and vertical and horizontal rudders entirely to the fore of the propellers so that the maximum overall dimension of 60 the assembled propellers may be substantially the same as, or but slightly less than, the maximum diameter of the torpedo body or shell. By such a construction and arrangement of the essential elements of the 65 torpedo tail, a maximum power efficiency may be developed.

For the sake of simplicity the drawings show only such parts of the torpedo as are necessary to adequately illustrate my invention. Referring now to the illustrative embodiment of my invention, the hull of the torpedo afterbody is made up of two separate sections 1 and 2, the hull section 2 comprising the tail of the torpedo and, together 70 with a transverse partition 3, forming a chamber for the reception of exhaust gases which may be conducted from the torpedo engine to such chamber through conduits 4. A pair of parallel propeller shafts 5, adapted 75 to be simultaneously and uniformly rotated in opposite direction by the torpedo engine, extends through the tail section 2 and terminate aft of the end of the tail. To the ends of these shafts, the propellers 6, 80 each preferably having four blades, are attached. The diameter of the propellers and the center to center distance of the shafts 5 are such that the propeller blades overlap midway between the shafts, and also, such 85 that the maximum overall dimension of the assembled propellers may be substantially 90 as great as the maximum diameter of the torpedo body. Furthermore, the relative positions of the propellers upon the shafts are 95 such that in the rotation of the shafts the blades mesh with each other in a manner similar to the teeth of spur gears.

Vertical and horizontal vanes 7 and 8 project from the tail 2 and are provided at their 100 ends with vertical and horizontal rudders 9 and 10. As indicated, the vanes preferably terminate sufficiently short of the forward edges of the propellers to permit the rudders to be placed between the ends of the vanes 105 and the forward edges of the propeller blades, thus making it unnecessary to diminish the diameter of the propellers by the provision of members at their sides to support the rudders aft of the propellers.

- The continuity of the horizontal rudders 8 is interrupted by housings 11 for the propeller shafts 5, such housings being provided at their ends with suitable shaft bearings 12.
- 5 For the escape from the tail 2 of the exhaust gases led thereto, a conduit separate from the propeller shafts is provided, thus making it unnecessary to increase the diameter of the shafts beyond the size required
- 10 for structural purposes. In the present embodiment of my invention such an exhaust conduit or tube 13 is shown attached to the outer edge of the upper vertical tail vane 7. To afford a rigid construction, the tube 13 is preferably provided with a longitudinal slot adjacent to the vane to receive the outer edge thereof, the edges of the tube being subsequently welded or otherwise secured to the edges of the vanes. For further structural
- 15 rigidity the tubes may be provided with a plurality of rivets 14. By thus discharging the gases at a point above and midway between the propellers, the gases will not, by becoming intermingled with the water surrounding the propellers, interfere with their proper operation. If desired a second exhaust conduit 13^a may be attached to the lower vertical tail vane.

It will be observed of the torpedo thus shown and described that the arrangement and construction of the essential elements of the tail are such as to attain the aforesaid object of my invention.

According to the provisions of the patent statutes I have described the principle and operation of my invention together with the construction which I now consider to represent the best embodiment thereof. However, I desire to have it understood that my invention may be practised with other forms of construction than that specifically shown herein.

I claim as my invention:

1. In an automobile torpedo the combination with a hull of a pair of parallel eccentric propeller shafts, a pair of twin propellers secured one to the outer end of each shaft and in such position that the blades of said propellers overlap midway between said

Copies of this patent may be obtained for five cents each, by addressing the "Commissioner of Patents, Washington, D. C."

shafts, a vertically disposed tail vane attached to said hull substantially midway between said shafts but terminating short of the general plane of rotation of said propellers, and an exhaust conduit extending from said hull to a point above and substantially midway between the axis of rotation of said propellers.

2. In an automobile torpedo, the combination with a hull, of a pair of parallel eccentric propeller shafts, a pair of twin propellers secured one to each shaft, the blades of said propellers overlapping midway between said shafts, a vertically disposed tail vane midway between said shafts but terminating short of the general plane of rotation of said propellers, and an exhaust tube enveloping and secured to the outer edge of said vane.

3. In an automobile torpedo, the combination with a hull, of a pair of parallel eccentric propeller shafts lying in a common substantially horizontal plane, a pair of twin propellers secured one to each shaft, the blades of said propellers overlapping midway between said shafts, a pair of vertically disposed tail vanes midway between said shafts and extending one above and one below said plane thereof, and an exhaust tube secured to the outer portion of each of said vanes.

4. In an automobile torpedo, the combination with a hull, of a pair of parallel eccentric propeller shafts, a pair of twin propellers secured one to each shaft, the blades of said propellers overlapping midway between said shafts, vertical and horizontal tail vanes secured to said hull and provided at their ends with vertical and horizontal rudders, said rudders being to the fore of said propellers, and an exhaust conduit independent of said shafts.

In testimony whereof I have hereunto set my hand.

HAROLD W. SHONNARD.
